UNITED STATES PATENT OFFICE.

HARRISON C. HOWARD, OF CONIMICUT, RHODE ISLAND.

VALVE RECORDING AND INDICATING DEVICE.

No. 899,738.

Specification of Letters Patent.

Patented Sept. 29, 1908.

Application filed March 13, 1908. Serial No. 420,762.

To all whom it may concern:

Be it known that I, HARRISON C. HOWARD, a citizen of the United States, residing at Conimicut, in the town of Warwick, in the county of Kent and State of Rhode Island, have invented certain new and useful Improvements in Valve Recording and Indicating Devices, of which, the following is a specification, reference being had therein to 10 the accompanying drawing.

This invention relates to recording and indicating devices for valves, and has for its object to provide a simple, positive and effective means for indicating whether the valve is open or closed, and also to record the time 15 of movement and amount of opening through the valve.

This device may be used in connection with any valve but is designed more particularly for use on valves in a sprinkler system for fire protection.

It is found in practice that the valves in the water supply service often become closed, sometimes by accident or carelessness, 25 and sometimes by design, rendering the sprinkler system useless and the fact is not discovered until after a fire has destroyed the building. To avoid any possibility of such an accident happening, without the 30 knowledge of the authorities, I have provided an annunciator to be electrically connected to operate in the superintendent's office, or other distant locality, to indicate whether the supply valve is open or closed, 35 and a recording device is also provided and located comparatively close to the valve to record the time and amount of movement, and also to show the amount of opening through the valve.

With these and other objects in view, the invention consists of certain novel features of construction, as will be more fully described and particularly pointed out in the appended claims.

In the accompanying drawings: Figure 1— is a diagrammatic view illustrating a valve connected by a flexible shaft to a recording device and an annunciator connected to said recording device. Fig. 2— is an enlarged elevation showing the casing in section, illustrating the operating mechanism for the recording device, showing the pen in position to indicate open. Fig. 3— is a detail view showing the recording pen in 50 the act of moving inward from the open to the closed position and completing an elec-

tric circuit to move the pointer of the annunciator from the open to the closed position. Fig. 4— is a section on line 4—4 of Fig. 2 looking in the direction of the arrow, 60 showing the spiral for taking up the lost motion in the flexible shaft.

Referring to the drawings, at 1 is the valve which may be located in the main service pipe 2, or at any convenient place, and extending upward from the top cap of this valve is the frame 3 through which the valve actuating spindle 4 passes, the same being operated by means of the hand wheel 5. On this spindle 4 is located a gear 6 70 which meshes into a pinion 7, the latter being held to turn the pin 8 which receives its bearing in the bracket 9 attached to the framework 3.

At 10 is the casing of the recording device 75 which may be made in any desired form. The recorder is constructed in the usual way and consists essentially of a plate 11 mounted on the center pin 12 arranged to be rotated by a suitable clock mechanism, not 80 shown. On this plate is mounted a disk of paper 12^a lined off to indicate the twenty-four hours of the day, and marked to indicate closed at its center portion and open at its periphery. An arm 13 is provided having 85 a pen 13^a at its upper end, said arm being pivotally mounted at its lower end on the pin 14 (see Fig. 2) and has an outwardly extending arm 15 on the outer surface of which is formed a segment 16, the teeth of 90 which mesh with the threaded portion 17 on the shaft 18, said shaft being provided with bearings at 19 and 20, above and below its threaded portion. The lower end of this shaft is connected to the pinion pin 8 on the 95 valve 1 by means of the flexible shaft 21, whereby any movement of the valve stem 4 is communicated to rotate this shaft 18 and actuate the pen point 13^a across the face of the dial to indicate the position or opening 100 through said valve.

The fact that this recorder is connected positively by means of a flexible shaft to the valve limits to some extent the distance the same may be placed from the valve itself, I 105 have therefore provided an annunciator 36 which may be electrically connected and located at any desired distance away. This annunciator may be made in any desired or convenient form, but I have shown a simple 110 construction provided with a pointer 37 mounted with an armature 38 to oscillate on

a pivot 39, the same being actuated by means of electro-magnets 40 and 41 so that the pointer 37 will always indicate either open or closed. This annunciator is electrically connected to the indicating apparatus by means of the wires 35 and 35^a and may be located in the superintendent's office, or at any other convenient point, to indicate when the valve is opened or closed. In carrying out this portion of the invention I have provided a dog 22 of insulating material pivoted at 23 and normally held in a horizontal position by the tension of the spring 24 pressing against its flat side 25. Contact strips 26 and 27 are secured to the upper and lower edges of this dog, said strips being connected by the wires 28 and 29 to their respective binding posts 30 and 31, binding post 32 serving for the common return wire 33.

20. At 34 is a pin secured to the segment 16, which engages the contact strip 26 when the pen is carried towards the center or closed position, completing the circuit through the wires 29 and 35, energizing the magnet 40 which in turn attracts the armature 38 and pulls the pointer over to indicate that the valve is closed. While this may not be exactly the case, yet it indicates that the valve is not open as it should be and therefore requires attention. As the pen goes towards the center or closed position of the dial this pin 34 engages and tips down the dog 22, see Fig. 3, and passes beneath it, the annunciator showing closed throughout this inward stroke. Then when the valve is really being opened, the pen starts from its closed position and works outward. The contact pin will not be brought into connection with the contact strip 27 until said pen is nearly to its out or open position when this pin will engage the contact strip 27, complete the circuit to magnet 48 and draw the pointer to the open position, after which the dog is tripped up to allow the pin to pass into the 45 position illustrated in Fig. 2.

Another feature of my invention is the employment of a spiral spring 42, one end of which is fast at 43 to the case, while the opposite end is fast to the shaft 18. This spring is adapted to serve a double purpose, first to act upon the flexible shaft to take up any back-lash or lost motion in the same and cause the pen 13^a to indicate accurately the position of the valve, and the second function of this spring is, in case the flexible shaft should become broken or out of order, when the pen is pointing to the open position, this spring will at once act upon the shaft 18 and cause the pin 34 to engage the contact strip 26 and move the annunciator to indicate that the valve is closed, causing an investigation, when repairs will at once be made.

My improved device is of simple and practical construction and very effective in its

operation and may be applied to any valve on the market or already installed.

Having thus described my invention, what I claim as new and desire to secure by Letters Patent, is:

1. In a device of the character described, the combination of a valve, said valve being adapted to be manually operated, a recording device located at a distance from the valve, and means operatively connecting said valve with said recorder whereby the opening and closing of the valve will operate the recorder to indicate the extent of opening through said valve. 70

2. In a device of the character described, the combination of a valve, a recording device located at a distance from the valve and a flexible shaft connecting said valve with said recorder whereby the opening and closing of the latter will operate the former to indicate the extent of opening through the valve. 80 85

3. In a device of the character described, the combination of a valve, a recording device located at a distance from the valve, a flexible shaft connecting said valve with said recorder whereby the opening and closing of the latter will operate the former to indicate the extent of opening through the valve, and means for taking up the lost motion of said 90 95 shaft.

4. In a device of the character described, the combination of a valve, a recording device located at a distance from the valve and a flexible shaft connecting said valve with said recorder whereby the opening and closing of the latter will operate the former to indicate the extent of opening through the valve, and an annunciator controlled in its action by the operation of said recording 100 105 device.

5. In a device of the character described, the combination of a valve, a recording device located at a distance from the valve means connecting said valve with said recorder whereby the opening and closing of the latter will operate the former to indicate the extent of opening through the valve, and means controlled by the operation of the recording device to indicate closed if the motion transmitting connection to the valve should be broken. 110 115

6. In a device of the character described, the combination of a valve, a recording device located at a distance from the valve and a flexible shaft connecting said valve with said recorder whereby the opening and closing of the latter will operate the former to indicate the extent of opening through the valve, an annunciator controlled in its action 120 125 by the operation of said recording device, and a spring for taking up the lost motion of said shaft, said spring being also adapted to move the annunciator to indicate closed.

7. In a device of the character described, 130

the combination of a valve, a recording device having a rotatable dial, a recording pen, a flexible shaft connecting said valve with said recording device whereby the opening 5 and closing of the valve will move the pen over the dial to indicate the extent of opening through said valve, an annunciator electrically connected to said recording device and controlled in its action by the movement 10 of said pen.

8. In a device of the character described, the combination of a valve, a recording device having a rotatable dial, a recording pen, a flexible shaft connecting said valve with 15 said recording device whereby the opening and closing of the valve will move the pen over the dial to indicate the extent of opening through said valve, an annunciator electrically connected to said recording device 20 and controlled in its action by the movement of said pen and means for automatically moving both the pen and the annunciator to the closed position if said shaft should become broken.

25 9. In a device of the character described, the combination of a valve, a recording device having a rotatable dial, a recording pen,

a toothed segment for operating said pen, a threaded shaft engaging said segment and a flexible shaft connecting said valve with said threaded shaft whereby the opening and closing of the valve will operate said threaded shaft to move the pen over the dial to indicate the extent of opening through said valve. 30

10. In a device of the character described, the combination of a valve, a recording device having a dial, a recording pen, a toothed segment for operating said pen, a threaded shaft engaging said segment and a flexible 40 shaft connecting said valve with said threaded shaft whereby the opening and closing of the valve will operate said threaded shaft to move the pen over the dial to indicate the extent of opening through said valve, and an 45 electrically operated annunciator controlled in its action by the movement of said pen.

In testimony whereof I affix my signature in presence of two witnesses.

HARRISON C. HOWARD.
